TAMPING TOOL

FIELD OF THE INVENTION

The fields of art to which the invention pertains include the fields of cigarette making and tobacco tamps.

BACKGROUND AND SUMMARY OF THE INVENTION

In a modern version of a portable, single unit cigarette making machine, tobacco is placed within a mold chamber having a as a long dimension the length of the tobacco portion of a cigarette and having an end portion formed to receive a filter plug. A levered mechanism is then utilized to mold the tobacco and filter plug to a proper cylinder thickness. An ejection component slides the product into an aligned envelope of cigarette paper. While such a device is easier to use than the traditional roller mechanisms, if insufficient tobacco is placed in the mold the cigarette produced is loosely packed resulting in a poor smoke. In the traditional roller mechanism, the cigarettes produced are uniformly dense, the width of the cigarette varying with the amount of tobacco placed on the roller. However, in the modern mold machine as described, the cigarette paper envelopes are of uniform diameter and cannot be narrowed to compensate for slack. Accordingly, it is desirable to tightly pack tobacco within the mold. However, when tobacco is merely spread in the mold and tamped with the fingers, the density tends to vary along the length of the cigarette. Furthermore, in order to place sufficient tobacco in the mold, it is found that when the mold is closed, a substantial amount of tobacco pieces have portions left outside the mold. Many such pieces are continuation of strands which have been trapped within the mold and during ejection of the molded tobacco the excluded portions drag on the included portions resulting in a disturbance of the even distribution of the tobacco. Furthermore, the excluded portions constitute tobacco which is not utilized and therefore is wasted.

The present invention provides a tool for use with such molding machines for eliminating the aforementioned problems and for enabling well packed, uniformly dense cigarettes to be repeatedly prepared with a minimum of concentration on the part of the user. In particular, the present invention provides a tamping and aligning tool in which the functional components are integrated into a single tool of very simple construction but which functions altogether in a manner not entirely obtainable with its components separated.

Specifically, a tool is provided for tamping and aligning tobacco in a cigarette molding machine, comprising in integrated combination a tamp base, a fingergrip member upright from the base and an insertion member extending from the vertical end of the fingergrip member. The base has a length of about one-half to one times the length of the tobacco portion of a fully formed cigarette and a width of about one to two times the width of a cigarette. The fingergrip member has sufficient vertical extent from the base for grasping between a user's fingers. The insertion member is tapered from the fingergrip member to form a relatively narrow outer edge.

In use, the fingergrip member is held with the tamp base down and sufficient tobacco is placed within the mold to provide a dense cigarette when entirely utilized. The base is then inserted into the mold and the

tobacco tamped uniformly with one or two strokes. The mold is then closed and, during closing, the tool is turned around, the fingers now grasping the base and the insertion member is utilized to sweep pieces of tobacco within the mold as it is being closed so that upon closing there is no tobacco outside of the mold, but all of the tobacco is uniformly distributed within the mold. The result is a perfectly formed, uniform density cigarette.

BRIEF DESCRIPTION OF THE DRAWINGS

FIG. 1 is a perspective view of a portable, single unit mold machine and tamping tool, the mold machine including tobacco and a filter plug, cut away for clarity;

FIG. 2 is a cross-sectional view of the mold machine and tamping tool, taken on line 2-2 of FIG. 1, in the direction of the arrows, but with the tamping tool inserted within the mold cavity;

FIG. 3 is a perspective view of the mold machine and tamping tool in the process of closing the mold machine and with the tamping tool reversed and positioned for a sweeping action;

FIG. 4 is a cross-sectional view taken on line 4-4 of FIG. 3, in the direction of the arrows;

FIG. 5 is a bottom view, partially cut away, of the cigarette machine during ejection of a tobacco plug; and

FIG. 6 is a perspective view of an alternative tamping tool structure in accordance with this invention.

DETAILED DESCRIPTION

As required, details of illustrative embodiments of the invention are disclosed herein. However, it is to be understood that these embodiments merely exemplify the invention which may take forms different from the specific illustrative embodiments disclosed. Therefore, specific illustrative embodiments are not necessarily to be interpreted as limiting, but as a basis for the claims. Furthermore, while the invention will be described with respect to a molding machine of specific structure, it is to be understood that the molding machine per se forms no part of this invention and that the invention can be utilized with molding machines of other, like construction.

Referring now to FIGS. 1 and 2, there is shown a tobacco molding machine 10, including a housing defining a mold chamber 12 for the tobacco 14, and a compartment 16 in communication with the tobacco chamber 12, in which a filter plug 18 is disposed. The machine includes a movable mold half 20 and connecting lever mechanism 22 for moving the mold half 20 into the mold cavity 12, decreasing the mold cavity until it assumes the size and shape of a fully formed cigarette (See FIG. 4).

The tamping tool comprises a base 24, a fingergrip member 26 upright from the base, and an insertion member 28 extending from the vertical end of the fingergrip member 26. The base has a length of about one-half to one times the length of the tobacco portion of a fully formed cigarette and a width of about one to two times the width of a cigarette. The fingergrip member extends from the base a sufficient vertical extent for grasping between a user's fingers so that the base may be placed within the mold cavity 12 and the tobacco therein tamped downwardly to form a dense, tightly packed plug of tobacco. By making the base at least one-half the length of the tobacco portion of the cigarette, no more than two tamping actions need be used.

In this particular embodiment, the base has a length which is substantially the length of the tobacco portion and therefore a single tamping action only need be used and this aids in making a uniformly packed cigarette. The width of the base depends upon the width of the mold cavity, but the base generally should be about one to two times the width of the cigarette. In terms of actual measurement, the base is about 3.5 - 8 centimeters in length and about 0.5 - 1.6 centimeters in width, depending on the particular dimensions of the molding machine. The particular base illustrated is about 7 centimeters in length and about 1 centimeter in width.

The upright member is advantageously disposed centrally on the base so that uniform pressure can be applied along the entire length of the base 24 by simply pushing down on the upright member 26. In particular, the upright member is about 1 - 10 centimeters long, with a comfortable range being about 3 - 7 centimeters.

Referring now to FIGS. 3 and 4, after the tobacco has been properly tamped into the chamber 12, the mold half 20 is pushed forward by means of the mechanism 22 so that the mold cavity is almost completely covered, leaving only a slit 30. At this stage, a large number of tobacco pieces have been caused to be moved upwardly out of the mold cavity as a result of the lateral pressure while the mold half 20 is moved within the cavity 12. These tobacco pieces lay on top of the exposed mold half 20 and some of the pieces have continued portions within the mold cavity. These pieces ordinarily would cause a drag on the tobacco within the mold cavity during ejection of the tobacco plug, causing non-uniformity along the cigarette length. In order to prevent such drag from occurring, and to save tobacco, the tamping tool is inverted, as shown, so that the insertion member 28 is in a downward position. The insertion member is tapered to form a relatively narrow outer edge 32, generally less than about 0.2 centimeters thick, and is used, as illustrated, to sweep tobacco pieces into the mold cavity and to free the tobacco pieces from the edge of the mold half 20 as the mold half 20 is being closed.

Referring now to FIG. 5, it will be seen that the component defining the mold cavity 12, opposite the mold half 20 is a movable member 34 having a generally half cylindrical cross section (see FIGS. 3 and 4) and a tapered end 36. The tapered end 36 extends into a tapered guide member 38 on which is placed an envelope 40 of cigarette paper. A lever 42 is connected to the rear end of the half cylindrical mold half 36 and is pushed in the direction of the arrow 44 to carry the tobacco plug out of the machine and into the waiting envelope 40, whereupon a fully formed cigarette is obtained.

Referring now to FIG. 6, an alternate embodiment is disclosed which is very similar to the embodiment referred to above in terms of dimensions, but in this particular embodiment, the base 46, fingergrip member 48 and insertion member 50 are formed as a single unit of one-piece construction for example, of injection molded plastic.

I claim:

1. A tool for tamping and aligning tobacco in a cigarette molding machine, comprising in integrated combination:

an elongate tamp base having uniform length and width to define a substantially planar, rectangular tamping surface, said surface being about one-half to one times the length of the tobacco portion of a fully formed cigarette and said width being about one to two times the width of said cigarette; a fingergrip member upright from said base of sufficient vertical extent therefrom for grasping between a user's fingers; and an insertion member extending from the vertical end of said fingergrip member and tapered to form a relatively narrow outer edge.

2. The invention according to claim 1 in which said fingergrip member has substantially greater length than width.

3. The invention according to claim 1 in which said fingergrip member is substantially narrower than said base along the long dimension of said base.

4. The invention according to claim 3 in which said fingergrip member is disposed centrally on said base.

5. The invention according to claim 1 in which said tool is formed as a single unit of one-piece construction.

6. The invention according to claim 1 in which the outer edge of said insertion member extends along a plane parallel to the plane of said tamping surface.

7. The invention according to claim 1 in which said base is about 3.5 - 8 centimeters in length and about 0.5 - 1.6 centimeters in width.

8. The invention according to claim 7 in which said fingergrip member is about 1-10 centimeters long.

9. The invention according to claim 7 in which the outer edge of said insertion member is less than about 0.2 centimeters thick.

10. The invention according to claim 7 in which said fingergrip member is about 1-10 centimeters long, about $\frac{1}{2}$ -2 centimeters wide and is centrally disposed on said base, the outer edge of said insertion member is less than about 0.2 centimeters thick and extends along a plane parallel to the plane of said tamping surface.
